The ornamental design for an adjustable divider for use in vehicles, as shown and described.

DESCRIPTION

FIG. 1 is a front perspective view of an adjustable divider for use in vehicles, showing my new design;

FIG. 2 is a front view thereof;

FIG. 3 is a back view thereof;

FIG. 4 is a right side elevation view thereof;

FIG. 5 is a left side elevation view thereof;

FIG. 6 is a top view thereof; and,

FIG. 7 is a bottom view thereof.

The broken lines illustrate portions of the adjustable divider for use in vehicles which form no part of the claimed design.
